ATTORNEY

UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,374,327.

Specification of Letters Patent. Patented Apr. 12, 1921.

Application filed February 6, 1919. Serial No. 275,391.

To all whom it may concern:

Be it known that I, EDWARD R. SARGENT, a citizen of the United States, residing in the city and county of New Haven, State 5 of Connecticut, have invented certain new and useful Improvements in Casket-Handles, of which the following is a full, clear, and exact description.

This invention relates to the construction 10 of a composite arm consisting of a main plate and a finishing or decorating plate secured thereto, and it has particular reference to the construction of a pivoted arm for casket handles or the like.

15 A number of the cheaper grades of casket handles now in use are constructed with pivoted arms consisting of a main plate of steel or similar metal for pivotally connecting the handle bar to a fixed socket 20 and with a finishing plate for covering the main plate to give the same a massive and more pleasing appearance.

25 The primary object of my invention is to provide simple but satisfactory means for securing the so-called finishing plate in place upon the edge of the main plate.

To this and other ends, the invention consists in the novel features and combinations 30 of parts to be hereinafter described and claimed.

In the accompanying drawing:

Figure 1 is a front elevation of a casket handle embodying my invention, showing part of the handle bar.

35 Fig. 2 is a vertical sectional view of the same.

Fig. 3 is a rear view of the pivoted arm removed from its base or socket plate.

40 Fig. 4 is an edge view of the main plate of the pivoted arm, and

Fig. 5 is a sectional view taken on line 5—5 of Fig. 2 looking in the direction of the arrows.

45 In the embodiment of my invention illustrated in the drawing, I have shown a base or socket plate 10, preferably made of sheet metal having rearwardly turned marginal portions to rest against the wall of the casket or box, and this plate is provided 50 with the customary screw holes 11 at the lower part thereof, through which the attaching screws (not shown) are passed. At the lower middle part of the plate 10, the same is provided with an opening for the 55 passage of the pivoted arm 12. Inside of

the socket plate 10 and adjacent this opening, may be mounted an arcuate bridge piece 13, the opposite ends of which are preferably rigidly secured to the socket plate by means of rivets 14. The pivoted 60 arm 12 consists preferably of a main plate 15 and of a finishing plate hereinafter described for covering the edge of the main plate. The upper end of the main plate is pivotally connected to the socket plate 10, 65 in the particular device illustrated by means of the radially projecting lug 16, which passes through a slot formed in the bridge piece 13 and may be retained in engagement therewith by a pin 16' extending 70 through the end of the lug 16 and positioned to engage the rear face of the bridge piece 13, as shown in Fig. 2, or the main plate may be pivotally connected to the bridge plate by any other preferred means. The 75 outer end of the main plate 15 preferably has a relatively large circular opening formed therethrough adapted to receive the handle bar 17, which bar is preferably reinforced by a wooden bar 17'. The handle 80 bar may be conveniently held against longitudinal movement through the plate 15 by means of a screw 18 passing through a drill hole formed in the lug 19 projecting laterally from one face of the sheet metal 85 arm 15 and screwed into the wooden bar 17'.

The structure so far described is more clearly shown and described in my copending application, Serial No. 172,466, filed June 2, 1917, and need not be more specifically herein set forth, since it forms no part 90 of this invention. This invention, as above stated, relates to means for securing the finishing plate 20 to the main plate 15 of the arm 12, and the particular use of the arm 95 12 or the manner in which the same may be connected to a base or socket plate, such as 10, or have a handle bar 17 secured to the same, is immaterial, so far as my present invention is concerned.

100 The main plate 15 of the handle 12 is preferably constructed of sheet metal sufficiently strong to withstand the strain that may be exerted upon the same by the handle bar 17, and in order to produce a pivoted arm which may be cheaply constructed, but at the same time will present a massive and pleasing appearance, the plate 15 has its upper edge covered by a finishing plate 20. 105 The main plate 15 has provided at each 110

end thereof a laterally projecting lug 21, which may be conveniently formed by stamping out the plate 15, so that a lug is formed at each end thereof, which lugs 5 may then be bent at right angles to a lateral face of this plate. The finishing or decorating plate 20, if desired, may be made of very thin metal, since it is not likely to be submitted to any appreciable strain and the 10 same may be either straight or curved in cross-section, as desired. The means which I have provided for securing this finishing plate upon an edge of the main plate consist in forming a longitudinal slot in each 15 end of the finishing plate 20, as designated by the numeral 22 in Figs. 3 and 5. A pair of tongues 23 is thus formed at each end of the plate 20, which may be bent inwardly to straddle the edge of the main plate 15, and 20 in order to firmly secure the finishing plate 20 in position upon the main plate, one of the tongues 23 may be bent around the lug 21 in rigid engagement with the same, as shown more particularly in Fig. 2. The ar- 25 rangement herein described, by which the tongues 23 are formed to straddle the opposite ends of the main plate 15, tends to retain the finishing plate in place upon the edge of the main plate 15, but in order to 30 securely fasten the plate 20 in this position, it is desirable to bend a tongue at each end of the finishing plate into clamping engagement with the lug 21, as above pointed out.

From the above description, when read in 35 connection with the drawing, it will be apparent that I have provided a very simple and inexpensive, but satisfactory means, for securing a finishing or decorating plate upon the edge of its main plate.

40 What I claim is:

1. A composite arm for casket handles or the like, comprising a main plate, a finishing plate embracing the edge of said main plate to cover the same, and means for 45 securing said finishing plate in place upon said main plate, comprising laterally pro-

jecting lugs upon one of said plates, and tongues upon the other plate bent into embracing engagement with said lugs.

2. A composite arm for casket handles or 50 the like, comprising a main plate, a finishing plate covering and embracing the edge of said main plate, means for securing said finishing plate in place upon said main plate, comprising tongues upon the ends of said 55 finishing plate, and coöperating lugs upon the other plate, extending transversely of the plane of said plate and positioned to have said tongues bent into locking engagement therewith.

3. A casket handle arm comprising a sheet metal plate, a finishing plate embracing the edge of said sheet metal plate to cover the same, means for securing one plate in place upon the other, comprising laterally bent 65 lugs upon the first mentioned plate, bent out of the plane of the same, and positioned adjacent the ends of the other plate, and tongues upon said finishing plate bent into embracing engagement with said lugs. 70

4. A composite arm for casket handles or the like, comprising a main plate, a finishing plate engaging the edge of said main plate to cover the same, means for securing said finishing plate in place upon said main 75 plate, comprising lugs upon said main plate, the ends of said finishing plate being returned to embrace said lugs.

5. A composite arm for casket handles or the like, comprising a main plate, a finishing 80 plate mounted upon a lateral edge of said main plate to cover the same, means for securing said finishing plate in place upon said main plate, comprising lugs upon said main plate at the opposite ends thereof and 85 having the end portions of said finishing plate bent into embracing engagement with said lugs.

In witness whereof, I have hereunto set my hand on the 3rd day of February, 1919. 90

EDWARD R. SARGENT.
